G. F. HUNTER.
ELECTRIC CIRCUIT BREAKER.
APPLICATION FILED MAR. 27, 1920. RENEWED OCT. 11, 1922.

GEORGE F. HUNTER,
INVENTOR

BY *Rowright*.

ATTORNEY.

UNITED STATES PATENT OFFICE.

GEORGE F. HUNTER, OF PORTLAND, OREGON.

ELECTRIC-CIRCUIT BREAKER.

Application filed March 27, 1920, Serial No. 369,163. Renewed October 11, 1922. Serial No. 593,894.

To all whom it may concern:

- Be it known that I, GEORGE F. HUNTER, a citizen of the United States, residing at Portland, in the county of Multnomah and 5 State of Oregon, have invented a new and useful Improvement in Electric-Circuit Breakers, of which the following is a specification, reference being had to the accompanying drawings.
- 10 My invention relates to circuit breakers as a class.
- The object of my invention is to provide a circuit breaker wherein the parts are arranged in a manner that when the breaker 15 is heated to a pre-determined degree it will open the circuit and when its temperature is reduced to said degree, or below, it will close the circuit. These objects, as well as others, I accomplish by the construction, combination 20 and arrangement of parts illustrated in the accompanying drawings which form a part hereof.

The single figure illustrates a curling iron, with parts in section, and a side view of the 25 circuit breaker associated therewith.

The instrument is a curling iron of a common type. It has a handle 1 and heating iron 2, having a clasp 2'. In the end of the handle a socket of common form is provided. 30 The metallic part 3 of the socket forms one terminal and the opposing insulated terminal 4' is within the socket as shown. These receive the plug at the ends of wires extending from a source of electric energy. A conducting wire 4 extends from the terminal 4' to a connection with a resistance coil 5 in the heating iron 2. The return conducting wire 6 of the coil 5 extends to an insulated, rigidly secured contact terminal 7 in the central 35 part of the handle 1. A conducting wire 3' extends from the terminal 3 to an insulated securing means 8 to which it is fastened. An angled, thin metal arm 9 is rigidly fastened at its shorter end within the securing 40 means 8. The longer free end extends forwardly in the handle to a position opposite the terminal 7. In the free end of the arm a threaded contact pin 10 is rotatably positioned. A coil spring 11 is placed about it 45 to prevent it from rotating from a set position. The pin has a slotted head or any convenient arrangement to facilitate rotating it. An opening 12 is provided in the handle to supply means of access to the pin. 50 The arm 9 is of a desired thickness and length, and the contact terminal 7 is ar-

ranged in a position oppositely disposed to the inner end of the pin, which is adjustable toward said terminal.

It will be seen that when the iron 2 attains a desired heat, the pre-determined form and arrangement of the arm 9, is such that the said heat, being conducted through the iron 2 to its base in the handle will cause the arm 9 to acquire a temperature which 60 will cause it to expand and the pin to recede from the terminal 7, thus opening the circuit. It will also be seen that when the temperature in the arm 9 is reduced to a desired degree, it will contract and cause the 65 pin 10 to again engage the terminal 7 and close the circuit. It will be understood that the pin is first adjusted to a position wherein it will retain the circuit closed until the 70 said desired temperature is attained when 75 it automatically opens the circuit as stated. It is intended that the arm 9 shall have a short part and a longer part of desired lengths, the metal being of a predetermined temper. When an arm of this form is thus 80 bent, the metal on the inside of the angle is compressed and that on the outer side expanded. Upon the arm being heated, the 85 thermal action causes the metal on the inside of the angle to expand more than that on the outside of the same, which has been stretched in shaping the arm. This thermal action causes the longer part to warp away and draws the pin 10 from the terminal 7, thus 90 breaking the circuit. As the temperature 95 of the arm decreases, the action of the integral metal parts about the angle is reversed and the arm moves the pin again into contact with the terminal 7. I contend that the single arm circuit breaker, of a form and 100 length related to the laws of thermal action, furnishes a very sensitive and efficient means for breaking the electric circuit whenever the temperature in adjacent parts of any instrument to which it is adapted, has risen 105 to a predetermined degree. The device can be adapted to electric ovens, flat irons or any utensil in which heat is produced by electric energy.

I claim—

105 In an electrical circuit having opposing terminals and a resistance coil in the circuit arranged to diffuse heat therefrom, an angled metal arm of pre-determined temper, formed with long and short parts of desired 110 lengths and thickness, the short part being rigidly connected with one of the circuit

terminals, the free end of the longer part having a contact point therein oppositely disposed to the other circuit terminal, the arm being formed and arranged so that upon receiving heat therein the metal about the

5 inside of its angle will be thermally expanded and allow the longer part of the arm to warp and draw its contact point free of

the opposing terminal and, when the heat decreases, will contract and allow the contact 10 point to engage said terminal.

GEORGE F. HUNTER.
